UNITED STATES PATENT OFFICE

WILLIAM R. PETERSON, OF CHICAGO, ILLINOIS, ASSIGNOR, BY MESNE ASSIGNMENTS, TO BATES VALVE BAG CORPORATION, OF CHICAGO, ILLINOIS, A CORPORATION OF NEW JERSEY

AUTOMATIC CEMENT PACKING MACHINE

Application filed July 20, 1927. Serial No. 207,152.

This invention relates to automatic means for filling and weighing valve bags with cement or similar pulverulent material. More particularly, it relates to means for mechanically placing the machine in condition to start filling, upon the operator moving a starting handle, and for automatically stopping the feeding and discharging the bag when the proper weight of material has 10 been filled into the bag.

Details of the invention will appear as the description proceeds.

In the accompanying drawings forming a part of this specification, Figure 1 is a vertical cross-section of apparatus embodying the invention; Fig. 2 is an enlarged portion of Fig. 1 showing in detail the major portion of the mechanism embodying the invention; Figs. 3, 4 and 5 are views somewhat similar to Fig. 2, but showing the parts in different positions which they assume during the operation of the apparatus; Fig. 6 is an enlarged detail showing the lower part of the mechanism disclosed in Fig. 1, and showing the parts in discharging position.

The apparatus to which the invention is shown applied comprises a hopper 10 for containing cement or other pulverulent material to be fed into bags. This hopper is supported upon any suitable frame 11. In the upper end of the hopper there is a feeding shaft 12 having suitable means, not shown, mounted thereon for feeding material downward into the hopper. At the lower end of the hopper there is a propeller shaft 13 having thereon a suitable propeller, not shown, for discharging the material from the hopper through an outlet opening 14. A gate 15 is provided for closing this outlet opening when the discharging of material is to be stopped.

A lever 16 is fulcrumed upon the frame at 17 and has a lug 18 to which the gate is attached by a pivotal connection 19. A spring 20 is attached at 21 to the lower end of the gate and to a stud 22 fixed on the frame, so that the spring normally pulls the gate towards closed position.

An A shaped frame 23 is mounted in front of the opening. Scale beams 24 fulcrumed at 25 are provided at their ends with pivotal

connections 26 upon which the legs of the A frame rest. The upper end of the A frame is held in proper position by a link 27 which connects it with the main frame. A cross piece 28 between the legs of the A frame carries a spout 29 around which the valve of a bag may be placed, and which is brought into registry with outlet opening 14 when a bag is to be filled.

The legs of the A frame have downward extensions 30. A support 31 for the bottom of the bag is mounted upon these downward extensions. In the construction shown the edges of the downward extensions are provided with notches 32. A pivot lug 33 on each side of the bottom is adapted to enter one of these notches. A bottom supporting bracket 34 has one end 35 adapted to enter one of said notches and an offset portion 36 adapted to contact the other side of extension 30. The end 37 of bracket 34 projects beneath the bottom support of the bag so as to maintain it normally in an approximately horizontal position.

For discharging the bag there is a tilting frame 38 having side members which are approximately L-shaped. The bottom arm 39 of this L-shaped frame is pivoted at 40 on a bracket 41 projecting from the main frame. The long vertical arms 42 of the L frame 38 carry a cross piece 43 adapted to contact the side of a bag near its top.

Mounted above the gate there is a rock shaft 44. A lever 45 is fulcrumed upon this rock shaft. An arm 46 projects from the lower end of the L frame and is connected by a link 47 with lever 45. A bracket 48 is attached to link 47 in such a way that it is adjustable vertically. Bracket 48 carries a roller 49 in position to contact a lug 50 on the bottom support when the link is raised.

Feed shaft 12 carries an eccentric 51 which is connected by a link 52 to an arm 53 on rock shaft 44. A discharging arm 54 extends from rock shaft 44 and carries a lug 55. A pawl 56 is pivoted at 57 on lever 45 and has a tooth 58 in position to engage lug 55 when a bag is to be discharged. From the lower end of pawl 56 there extends an approximately horizontal arm 59. A spring 60 is

interposed between this horizontal arm of the pawl and a lug 61 on lever 45, so as to normally press the horizontal arm downward.

A lock 62, for normally holding the pawl 5 out of operative position, is pivoted at 63 on the frame, and has a stud 64 normally engaging the horizontal arm of the pawl and holding it up against the pressure of spring 60. A catch 65 is pivoted at 66 on the frame 10 and has a notch 67 in which there normally rests a plate 68 on member 62, thereby holding the member in its locking position. A spring 69 is attached at 70 to catch 65 and to a pin 71 on the frame and holds the catch 15 in engagement with the locking member.

A trip bracket 72 is pivoted to the frame at 73. The free end of the trip bracket has a supporting catch 74 pivoted thereto at 75, and adjustable about the pivot. The lower 20 end 76 of the supporting catch is adapted to rest upon a wear plate 77 mounted on the A frame, when the bag is in filling position.

Lever 16 has an arm 78 projecting upward therefrom at its free end. Arm 78 is provided with a roller 79 beneath which there works a projection 80 from the trip bracket.

A roller 81 is mounted on the trip bracket in position to co-operate with a tripping member 82 for the lock catch. The upper end 30 of member 82 carries a stud 83 adapted to rest in a notch in catch 65.

Pawl lock 62 has a forwardly extending arm 85 carrying a lug 86 in position to be contacted under suitable circumstances by 35 a lug 87 which is an extension of lever 45 and projects from the rock shaft in an opposite direction from arm 54.

Above the tripping bracket there is an arm 89 projecting from rock shaft 44 and carrying a link 90. A lifting catch 91 is pivoted at 92 to link 90 and has a notch 93 in position to engage a stud 94 on the trip bracket, under suitable conditions. A link 95 is pivoted at 96 to lifting link 90 and at 97 to the frame. 45 The free end of link 95 carries an abutment 98. A spring 99 attached to link 90 and to lifting catch 91 normally draws the catch against abutment 98.

A starting handle 100 is pivoted at 101 to 50 the main frame and has an upwardly extending forked arm 102. A starting trip 103 is pivoted at 104 to the main frame, and has projecting therefrom a stud 105 between the forks of arm 102. The upper end 106 of 55 starting trip 103 is in position to operate catch 91 under proper conditions. A spring 107 is attached at 108 to the starting trip and its other end 109 is hooked about the fulcrum pin 101 of lever 100. The starting trip has 60 a heel 110 carrying a set screw 111 in position to abut a lug 112 on the frame when the trip is in one position. A set screw 113 through lug 112 is adapted to form a stop for trip 103 when the trip is in its normal, or non-active, position.

Starting handle 100 is provided with a lug 114 adapted to be engaged by a lug 115 on lever 16 when the lever is raised. Lever 16 has an end 116 projecting upward from its fulcrum and carrying a wear block 117 in position to contact a stop 118 on the main frame when the lever is in its gate-closing position. 70

The operation of the mechanism will now be described. Starting with the mechanism 75 in the position in which it is shown in Fig. 1, it will be seen that rock shaft 44 will be oscillated continuously by the continuously driven eccentric on shaft 12, but that this does not result in any operation of the other parts of 80 the mechanism because pawl 56 is held out of engagement with lug 55 and lifting catch 91 is held in inoperative position by spring 99, and furthermore, bracket 72 is in the position to which it is raised by lifting catch 91, and the catch has no function to perform with the parts in this position. It will be understood that a bag, not shown, is mounted upon spout 29 when the parts are in the condition shown in Fig. 1, and material is being propelled 85 through the outlet and spout into the bag. When a sufficient amount of material has been fed into the bag to cause movement of the scale beam, the A frame gradually descends. Upon the descent of the A frame, the trip 90 bracket moves about its pivot 73 and so draws the lower end of catch 74 towards the hopper and off of wear plate 77. Thereupon trip bracket 72 falls to the position in which it is shown in Figs. 3 and 4. When this occurs a 95 wear plate 119 on the rear end of the trip bracket is moved upward out of engagement with wear block 117 on end 116 of lever 16. This frees the lever and allows the closure of gate 15 by spring 20. 100

At the same time, roller 81 contacts trip 82 and moves catch 65 out of engagement with pawl lock 62. This allows spring 60 to move the toothed end of the pawl into position to engage lug 55 upon the next oscillation of 110 arm 54. When the pawl engages the lug during the upward movement of arm 54, lever 45 and link 47 are likewise raised. The consequent raising of arm 46 tilts the L-shaped frame forward to the position in which it is shown in Fig. 6, and the lifting of roller 49 against lug 50 tilts the bottom support to the position in which it is shown in Fig. 6. Tilting the bottom relieves tension of the bag 120, partially indicated in dotted lines in Fig. 6, on the spout and facilitates the discharging action of frame 38. The next downward oscillation of arm 54 returns the bottom support and the L-shaped frame to their normal positions. 115

When the trip bracket falls, roller 81, after 120 operating member 82, moves past that member, so as to allow its return to normal position, which is accomplished by a spring 121 connecting it with catch 65. When arm 54 is 125

raised arm 88 is lowered and lug 87 contacts lug 86 and returns the lock to its normal position, where it is held by catch 65, so that the pawl is released upon the next downward movement of arm 54 and is not re-engaged until the catch is again operated. Pin 71 is extended into the path of plate 68, so as to prevent member 62 from oscillating so far, when tripped, as to move lug 86 out of the path of lug 87.

When gate lever 16 drops, it makes possible the lowering of handle 100. As will be readily seen, spring 107 being attached at points 108 and 109, which form in effect the ends of a toggle the knuckle of which is at 104, holds the lever 100 in its raised position, as shown in Figs. 1, 2 and 3, until it is desired to start the filling of another bag. After the operator has placed another bag upon the filling spout, lever 100 is depressed, with the result that end 106 of member 103 is moved forward against lifting catch 91. Spring 107, after the toggle is moved so that the spring passes forward of knuckle 104, forces end 106 forward until the catch contacts lug 94, or, if the catch is raised at the time above end 106, until set screw 111 contacts block 112. In the latter case, beveled end 122 of the catch contacts end 106 upon the next descent of the catch, so that the catch is forced forward into operative position. In either case, the lifting catch 91 is pressed forward against stud 94 when notch 93 is moved beneath it and in position to raise it upon the next upward movement of arm 89. Upon this upward movement the trip bracket is raised, extension 80 from the trip bracket acts upon roller 79 to raise the gate, and plate 119, which is yieldingly attached to the trip bracket, is moved to the right of plate 117, as shown in Fig. 5. Lug 115 encounters lug 114 and returns handle 100 to its upper position. Upon the downward movement of link 91, member 74 drops far enough, before contacting plate 77, to bring plates 117 and 119 into contact and free handle 80 from roller 79.

It will be readily seen that roller 81 may oscillate member 82 upon the raising of the trip bracket without affecting the position of catch 65, the forward movement of the upper end of member 82 being idle. Thus the parts are returned to the position in which they are shown in Fig. 1 and the cycle of operations is repeated.

From the above description it will readily appear that the described apparatus will start the filling of a bag upon the depression of handle 100, and automatically continue that filling until the proper weight of the material has been placed in the bag, and thereupon automatically close gate 15, dump the bag from the machine, and return the parts to proper position for filling another bag when a bag is placed upon the filling spout and handle 100 is again depressed.

It will be readily understood that various changes may be made in the mechanical movements hereinbefore described within the terms of the appended claims.

What I claim is:

1. Apparatus for filling valve bags comprising a filling spout adapted to enter the valve of a bag, mechanical means for forcing the bag from the spout when filled, and means controlling the operation of said mechanical means by the weight of material in the bag. 70

2. Apparatus for filling valve bags comprising a spout adapted to enter the valve at the top of a bag, a pusher adapted to contact the side of the bag beneath the valve, a source of power, and a one-operation clutch adapted to connect the pusher with the source of power to give the pusher one reciprocation. 80

3. Apparatus for filling valve bags comprising a spout adapted to enter the valve at the top of a bag, a pusher adapted to contact the side of the bag beneath the valve, a source of power, a one-operation clutch 90 adapted to connect the pusher with the source of power to give the pusher one reciprocation, and means controlled by the weight of the bag for closing said clutch. 95

4. Apparatus for filling valve bags comprising a spout adapted to enter the valve at the top of the bag, a support for the bottom of the bag, said support being pivoted near one edge, and power means for oscillating the other edge of said support about said pivot. 100

5. Apparatus for filling valve bags comprising a spout adapted to enter the valve at the top of the bag, a support for the bottom of the bag, said support being pivoted near one edge, mechanical means for oscillating the other edge of said support about said pivot, and means actuated by the weight of material in the bag for causing said mechanical means to operate. 105

6. Apparatus for filling valve bags comprising a spout adapted to enter the valve at the top of the bag, a support for the bottom of the bag, said support being pivoted near one edge, and mechanical means for oscillating the other edge of said support about said pivot, a source of power, a one-operation clutch connecting the source of power to said mechanical means, and means controlled by the weight of material in the bag for closing said clutch. 115

7. Apparatus for filling valve bags comprising a spout adapted to enter the valve at the top of the bag, a support for the bottom of the bag, said support being pivoted near one edge, and mechanical means for raising the other edge of said support with a filled bag thereon. 125

8. Apparatus for filling valve bags comprising a spout adapted to enter the valve 130

- at the top of the bag, a support for the bottom of the bag, said support being pivoted near one edge, and mechanical means for raising the other edge of said support, a 5 source of power, a one-operation clutch connecting the source of power to said mechanical means, and means controlled by the weight of material in the bag for closing said clutch.
- 10 9. Apparatus for filling packages comprising a spout adapted to convey material into a package, a propeller adapted to force material through the spout, a gate for closing the opening between the propeller and 15 spout, means constantly urging the gate to closed position, a device for opening the gate, a source of power, and a one-operation clutch for connecting the source of power with said device.
- 20 10. Apparatus for filling packages comprising a spout adapted to convey material into a package, a propeller adapted to force material through the spout, a gate for closing the opening between the propeller and 25 spout, means constantly urging the gate to closed position, a device for opening the gate, a source of power, a one-operation clutch for connecting the source of power with said device, and manual means to close 30 the clutch.
11. Apparatus for filling packages comprising a spout adapted to convey material into a package, a propeller adapted to force material through the spout, a gate for closing the opening between the propeller and spout, means constantly urging the gate to closed 35 position, a source of power, means connected to said source of power for opening the gate, and a catch adapted to hold the gate open 40 after it has been opened by said mechanical means.
12. Apparatus for filling packages comprising a spout adapted to convey material into a package, a propeller adapted to force 45 material through the spout, a gate for closing the opening between the propeller and spout, means constantly urging the gate to closed position, a source of power, means 50 connected to said source of power for opening the gate, a catch adapted to hold the gate open after it has been opened by said power means, and means controlled by the weight 55 in the bag to release said catch and allow the gate to close.
13. Apparatus for filling packages comprising a spout adapted to convey material into a package, a propeller adapted to force material through the spout, a gate for closing the opening between the propeller and spout, means constantly urging the gate to closed 60 position, a device for opening the gate, a source of power, a one-operation clutch for connecting the source of power with said device, manual means to close the clutch, a 65 catch to hold the gate open after it has been opened by said device, and means controlled by the weight of material in the bag for releasing the catch.
14. Apparatus for filling valve bags comprising a spout adapted to enter the valve of a bag, a discharge device adapted to force material out through the spout, a gate for the opening between the discharge device and the spout, an ejector for forcing the bag 70 from the spout, a spring constantly urging the gate towards closed position, mechanical connections for opening the gate, a source of power, a one-operation clutch for connecting the source of power with the means for opening the gate, a catch for holding the gate open after it has been opened by said means, a one-operation clutch for connecting the source of power with said ejector, and common means controlled by the weight of material in the bag for releasing the catch and allowing the gate to close and for closing the clutch operating the ejector. 75
15. Apparatus for filling valve bags comprising a spout adapted to enter the valve of a bag, a discharge device adapted to force material out through the spout, a gate for the opening between the discharge device and the spout, an ejector for forcing the bag 80 from the spout, a spring constantly urging the gate towards closed position, mechanical connections for opening the gate, a source of power, a one-operation clutch for connecting the source of power with the means for opening the gate, a catch for holding the gate open after it has been opened by said means, a one-operation clutch for connecting the source of power with said ejector, and common means controlled by the weight of material in the bag for releasing the catch and allowing the gate to close and for closing the clutch operating the ejector. 85
16. Apparatus for filling valve bags comprising a spout adapted to enter the top of a bag, a discharge device adapted to force material through the spout into a bag, a gate for the opening between the discharge device and spout, a spring constantly urging the gate towards closed position a support for the bottom of the bag pivoted on its side towards the outer end of the spout, an ejector adapted to contact the bag beneath the spout 90 on the side towards the discharge device, a constantly operating shaft above the spout, a one-operation clutch adapted to force the ejector in a direction to shove the bag off of the spout and to raise the rear edge of the bottom support and then to return said ejector and support to their normal position, a clutch adapted to connect means for opening the gate with the shaft, a catch for holding the gate open after it reaches open position. 95
- 100
- 105
- 110
- 115
- 120
- 125
- 130

tion, manual means for closing the last named clutch, and common means controlled by the weight of the material in the bag for releasing the catch and allowing the gate to close and for closing the first said clutch.

In testimony whereof, I have hereunto signed my name to this specification.

WILLIAM R. PETERSON.
